WILLIAM E. D. STOKES AND ONE-THIRD TO FREDERICK A. JONES, BOTH OF NEW
YORK, N. Y.

VALVE MECHANISM FOR ELEVATORS.

1,127,051.

Specification of Letters Patent.

Patented Feb. 2, 1915.

Application filed November 8, 1909. Serial No. 526,679.

To all whom it may concern:

Be it known that I, THURE LARSSON, a citizen of the United States, residing at Worcester, in the county of Worcester and State of Massachusetts, have invented a new and useful Valve Mechanism for Elevators, of which the following is a specification.

The object of this invention is to provide a new and improved valve mechanism for elevators, particularly hydraulic elevators of the type known as plunger elevators.

The special purposes of the invention are to simplify and improve the parts so that the elevator car can be very easily controlled and so that the same will be accurately and correctly stopped at the ends of its run.

To this end the invention consists of the parts and combinations of parts described in this specification and illustrated in the accompanying three sheets of drawings in which,

Figure 1 is a partial sectional view of a plunger elevator with improved mechanism applied thereto. Fig. 2 is a detailed view of the lever system employed at the bottom of the well for automatically stopping the car at the end of its downward travel. Fig. 3 is an elevation showing a modified form 25 that may be used for said lever mechanism. Fig. 4 is a plan view illustrating the arrangement of sheaves for the controlling levers. Figs. 5, 6 and 7 are detailed elevations of the lever system employed at the 30 top of the elevator well for stopping the elevator car at the limits of its upward travel, and Fig. 8 is a sectional elevation on an enlarged scale of the valve mechanism showing the main valve, pilot valve and the 35 automatic stopping valve.

The improvements will be best understood by a detailed description of the parts.

A cylinder A is sunk in the ground, which cylinder is of a length a little more than 45 the travel of the elevator. This cylinder A has a stuffing box on its top end fitting and sliding in which is a plunger C which carries and supports the car or platform D which is fitted to run up and down on 50 guides secured in the elevator well.

Attached to the top of the car are counter-balancing cables E which are trained over sheaves F journaled at the top of the elevator well.

55 Counter-weights G are attached to the

end of the cables E, which counter-weights are fitted to run up and down on ways secured to the side of the elevator well.

A to-and-fro connection pipe H communicates with the cylinder A. When water 60 under pressure is let into the to-and-fro pipe H the plunger is forced upwardly and the car ascends. When the to-and-fro pipe is connected to the exhaust, the weight of the car and plunger forces the water out of 65 the cylinder and the car descends. When the flow in the to-and-fro pipe is prevented the car and plunger are held stationary.

The valve arrangement consists of a main valve M, which controls the admission of 70 water under pressure to the cylinder to cause the car to ascend, which controls the flow of water from the cylinder to the exhaust to allow the car to descend and which stops the flow in the to-and-fro pipe to 75 hold the car stationary. The main valve is shown in its central position so that the flow to or from the elevator cylinder is stopped and the car held stationary. The main valve is operated by a motor piston 80 M', as shown in Fig. 8. The admission of pressure on the right side of the motor piston causes the main valve to move to the left, as shown in Fig. 8, to allow the pressure to flow into the elevator cylinder and 85 the connection of the exhaust with this side of the motor piston causes the main valve to move to the right to allow the elevator cylinder to connect to the exhaust.

The admission of the pressure or exhaust 90 to operate the motor piston M' is controlled and regulated by a pilot valve P. The pilot valve is controlled by a rope mechanism operated by a lever in the car.

An automatic stop valve S is interposed 95 between the main valve and the to-and-fro pipe H to stop the movement of the car automatically at the limits of its upward or downward travel. This automatic stop valve S is controlled by a cam arrangement 100 on the elevator car operating a system of levers and rods arranged in the elevator well.

The mechanism for operating the pilot valve from the car is arranged as follows:— 105 A lever I is mounted on a shaft J which is journaled in bearings on the main valve casing. Connected to one end of lever I is a rope K which is trained over a pulley L and under a pulley L' and is then carried up 110

the elevator well and trained over a sheave N and connected to a take-up weight O mounted so as to be capable of a vertical movement in ways at the top of the elevator well. Another rope K' is connected to the other end of the lever I and is trained over a pulley Q and under a pulley Q' and is then carried up the elevator well and trained over pulley R and connected to the take-up weight O. Pulleys L and Q' are mounted on a stud fixed in one end of an arm T, and pulleys L' and Q are mounted on a stud fixed in the other end of the arm T. The arm T is secured to a shaft U journaled in bearings on the bottom of the elevator car. A lever V is connected to the shaft U and is arranged to extend inside of the car or cage and to form the hand-operating or controlling lever by which the car attendant causes the car to go up or down or to be brought to a state of rest. This lever V co-operates with a suitable guide arranged inside of the car as shown. A movement of the lever V to the left, as shown in Fig. 1, moves the right-hand end of the lever I upwardly and the left-hand end downwardly. A movement of the lever V to the right moves the left-hand end of the lever I upwardly and the right-hand end downwardly. The weight O is heavy enough to keep the ropes K and K' under tension and to allow for any expansion or contraction thereof. By this means the operator can operate the pilot valve through the following connections. Forming part of the lever I, or secured on the shaft J of the lever I is a small lever 10 which connects by link 11 to a floating lever 12, the upper end of which is connected by a link 13 to the stem p of the pilot valve P and the lower end of which is connected to the stem m of the main valve M. These connections form restoring means which operate as hereinafter described to restore the pilot valve to central or closed position after the main valve has moved in the proper direction and distance called for by the movement of the lever V. The pilot valve casing is mounted on top of the main valve casing. This pilot valve has three ports; the left-hand one a, as shown in Fig. 8, connects with the pressure chamber in the main valve; the right-hand one b connects with the exhaust by an outside pipe X; and the middle one c connects with the right-hand side of the main valve casing through a passageway Z. The pilot valve consists of two packings 14 and 15 arranged on the stem p of the pilot valve and held in proper relative position by suitable bushings slid thereon. A washer is arranged on the end of the stem p and the bushings are held in place by a nut threaded on the end of the stem p. The middle bushing is turned down so as to allow a reduced section or area between the two packings 14 and 15. The packings and bushings slide or operate in a brass tubing t which is driven into the pilot valve casing and which has ports cut therein to communicate with the passages a, b and c. The brass tubing t is provided with 70 stuffing boxes at both ends so that the bushings will work tightly therein. When the left-hand end of the lever I, as shown in Fig. 8, is moved downwardly, the lever 10 is moved to the left and link 11 pulls lever 12 75 to the left, which through link 18 moves the pilot valve to the left. This connects the passage Z through ports a and c to the pressure and the pressure acting on the motor piston M' moves the main valve to the left 80 and allows water under pressure to flow to the elevator cylinder to cause the car to go up. As this movement of the main valve takes place, the main valve stem m will pull the lever 12 which, turning on link 11 85 as a fulcrum, will draw the link 13 and pull the pilot valve back to the right to its central or neutral position. When the left-hand end of the lever I, as shown in Fig. 8, is moved upwardly back to the position from which it was moved downwardly to cause the car to ascend the lever 10 will be rocked to the right and the pilot valve through link 11, lever 12 and link 13 will be moved to the right which will connect passage Z to the exhaust passage X through ports b and c. This will allow the main valve to move to the right until it comes back to its central or closed position, as shown in Fig. 8. As this action takes place 100 the link 12 turning on the link 11 as a fulcrum will restore the pilot valve to central position.

If it is desired to cause the car to go down, the lever 10 is rocked to the right 105 from its central position which will move the pilot valve to the right and again allow the main valve to move to the right to connect the to-and-fro pipe H to the exhaust. A movement of the lever 10 back to the position shown in Fig. 8 will cause the main valve to move back to its central position. The operation of these connections causes the main valve to move to the right or to the left to the same extent as the pilot 110 valve is moved to the right or to the left and then restores the pilot valve to its normal central or neutral position so that the movement of the main valve corresponds exactly with the movement of the lever 10 115 or with the movement of the lever V in the car.

The main valve consists of a sliding tube d screwed on the end of the main valve stem m. A bushing e is arranged on the tube d 120 and is held in place thereon by a reduced tube f engaging the right-hand end of which is the motor piston M', the parts being held in position by a nut g threaded on the valve stem m and pressing the parts up against a 125

shoulder *k* formed on the left-hand end of the main valve tube *d*. Connected to the main valve casing is a pressure pipe *i* and the exhaust pipe *j* and a to-and-fro passage *W* leads from the main valve casing and connects to the to-and-fro pipe *H* through the automatic shut-off valve *S* hereinafter described.

Arranged between the motor piston *M'* and the reduced bushing *f* is a packing 16. Arranged between the reduced bushing *f* and a shoulder on the bushing *e* is a packing 17. Arranged between the bushing *e* and the shoulder *h* on the tube *d* is a packing 18. The packing 16 causes the motor piston to fit tightly to the main valve casing and the packings 17 and 18 cause the main valve to work tightly. The packing 16 works in a brass bushing 140 driven on the right-hand end of the main valve casing and the packings 17 and 18 work in a brass bushing 150 driven in the left-hand end of the valve casing. Ports *k* are cut in this bushing 150. The tube *d* is bushed with brass and runs on a piston 19 which is secured to a stem 20 which is threaded into a cap or head *n* secured to the left-hand end of the valve casing. Pressure is admitted through openings 21 into the reduced bushing *f* and through openings 22 in the main valve tube *d* into the space 23 at the right of the piston 19. The piston 19 is made smaller than the motor piston *M'*. By this arrangement, when pressure is let on the right of the motor piston *M'* the main valve will be moved to the left, the water in the space 23 being forced through openings 22 and 21 back into the pressure. When the space at the right of the motor piston *M'* is connected to the exhaust, the pressure on the left of the motor piston *M'* will move the same to the right, the space 23 filling up through passages 21 and 22. The motor piston *M'* and the piston 19 thus form in effect a differential piston for giving the proper movements to the main valve. The packings 17 and 18 are arranged so that when the main valve is in its central position, the ports *k* will not be connected with either pressure or exhaust, as packings 17 and 18 will inclose the ports, and so that when the main valve moves to the left from the position shown in Fig. 8, pressure will flow through the main valve from pipe *i*, and so that when the main valve is moved to the right from the position shown in Fig. 8, the exhaust pipe *j* will be connected to the passage *W*.

The valves herein shown can be very economically manufactured, as the valve casings only have to be bored for one diameter and the parts can be very quickly and accurately assembled.

The automatic stop valve *S* consists of a casing 24 secured on the top of the main valve casing. A brass tube *l* is driven in the

same. Ports 25 are cut therein opposite the pipe *W* and ports 26 opposite the to-and-fro pipe *H*. The stop valve consists of a tube *s* which has shoulders fitting against which are valve heads *q* and *r* held in place by collars *u* and *u'*. A packing 27 is arranged between the valve head *q* and the collar *u* and a packing 28 is arranged between the valve head *r* and the collar *u'*.

Stems 29—29 are secured to the ends of the tube *s* by collars 290, which collars are threaded on the ends of the tube *s* and which have shoulders to hold the collars *u* and *u'* in position. These stems project out through stuffing boxes *v* secured to heads attached to the ends of the stop valve casing 24 and balance the valve hydraulically.

The operating mechanism hereinafter described may be connected to either stem 29—29 as the exigencies of the location demand. In the drawings the mechanism is shown as connected to the left-hand stem 29.

Holes 30 are arranged in the collars 290 so that the stop valve can move freely back and forth in the casing. Spring-pressed check valves 31—31 are arranged to cover openings in the tube *s*, the check valves being arranged to close toward the tube. When the elevator is going up, pressure is flowing from the pressure pipe *i* through the main valve through the pipe *W* to the pipe *H*. When the elevator reaches the limits of its upward movement by the automatic mechanism hereinafter described, the stop valve is moved to the left bringing the packing 28 to prevent flow through the ports 26 and thus stopping the flow of water between pipes *W* and *H* and stopping the upward movement of the elevator. When the operator in the car reverses the position of the main valve for the downward movement, pipe *W* is connected through the main valve to the exhaust pipe *j*. Then the flow from the elevator cylinder will start through pipe *H*, through the right-hand openings 30; 110 through the center of the tube *s* and out through the check valves 31—31 which will open to allow this flow to start. As the elevator starts on its downward movement the stop valve will be moved to its central or 115 inoperative position shown in Fig. 8, by the automatic mechanism hereinafter described, and when the car is fully on its downward movement, water will flow from pipe *H* through ports 26, ports 25 to the pipe *W* and out to the exhaust pipe *j* through the main valve. As the car approaches the bottom of its downward run the stop valve will be moved to the right by the automatic mechanism hereinafter described. This will cause the packing 27 to move to the right of the ports 25 and will check and stop this flow.

When the attendant on the car reverses the position of the main valve to allow pressure again to flow 130

into pipe W for an upward movement of the car, water will then flow through the left-hand openings 30, the center of the tube s and out through the check valves 31—31, 5 into pipe H. This will allow the car to start on its upward travel and as this travel takes place, the automatic mechanism hereinafter described will restore the shut-off valve to its normal central inoperative position 10 shown in Fig. 8. Thus the automatic valve will check and stop the elevator at the limits of its run either up or down but will allow the elevator to start in the opposite direction after it has been stopped by the automatic valve. It also will be seen that this 15 automatic stop valve can be easily manufactured as the same has to be bored for but one diameter.

The automatic mechanism for operating and controlling the stop valve is arranged as follows:—A lever 32 is mounted on a shaft journaled in bearings secured to the top of the valve casing 24. Secured on the ends of this shaft are levers 33 which connect by links 34 to one of the valve stems 29 of the shut-off valve. Connected to the ends of the lever 32 are rods 35 and 36 which are made in sections secured together by suitable couplings and which rods extend up at 20 the side of the elevator well. The rods 35 and 36 are connected preferably at the couplings to T-shaped levers 37, 38 and 39 arranged at the bottom of the elevator well and turning on studs or shafts secured to 25 supports or brackets *y* which are fastened to the side of one of the guides *z* for the elevator car. The downwardly extending arms of the T-shaped levers 37, 38 and 39 have rollers or shoes 40 arranged on their ends. 30 These downwardly extending arms of the T-shaped levers stand at slightly different angles so that the shoe 40 on the upper lever 39 is farthest to the right, as shown in Fig. 2.

45 Arranged on the elevator car are two guide pieces 41 and 42, the space between which forms a cam-way inclined from the top of the car to the bottom of the car toward the left. The ends of the guide pieces 50 41 and 42 are curved outwardly so that the inclined cam-way will have wide mouths to engage easily with the rollers or shoes 40. At the top of the elevator well are arranged three similar T-shaped levers 43, 44 and 45 55 which have similar rollers or shoes 40. These uppermost levers are shown in their normal position in Fig. 6. As the car approaches the upward limit of its run, the inclined cam-way first engages the shoe on 60 the lever 45 and swings the same to the left. Before the cam-way leaves this shoe it engages the shoe on lever 44 and continues the left-hand movement of the shoe or rollers 40, and as the car goes still farther up the 65 cam-way engages the shoe on lever 43 and

continues the left-hand movement of the rollers or shoes 40 until the car reaches the limits of its upward run to which the mechanism is set, which is indicated in Fig. 7. The principle of this motion is that after 70 the first engagement of the cam-way with the shoe or roller on the lever 45, the cam takes up and engages the next shoe on the lever 44 before it leaves the shoe on lever 45 and before the cam-way leaves the shoe 75 on the lever 44 it engages the shoe on lever 43. By this engagement an easy continued rocking motion is given to the levers as the car approaches the limits of its upward run and the parts can be adjusted so that the 80 stopping motion can take place in any desired movement of the elevator car, say a thirty-foot movement.

As the car moves downwardly from its upward limit of travel, shown in Fig. 7, to a 85 position where the cam-way progressively disengages the rollers or shoes on the levers 43, 44 and 45, the levers will be restored to normal position as shown in Fig. 6.

As the car reaches the bottom of its downward run the lower mouth of the cam-way will first engage the roller or shoe on lever 39 and will move the same to the right and then before leaving the shoe on lever 39 will engage the shoe on lever 38 and will continue the right-hand movement and then before leaving the shoe on lever 38 will engage the shoe on lever 37 and will still continue the right-hand movement of the shoes or rollers which will bring the lever 32 to 100 the position shown in Fig. 1.

The elevator car is shown at its lowest extreme in Fig. 1. As the car starts upwardly from its lowest position, the cam-way will disengage progressively from the 105 shoes on levers 37, 38 and 39 and will restore the operating system of levers to normal position shown in Fig. 6. Thus a very simple mechanism is provided for operating the automatic stop valve. Instead of using 110 a single T-shaped lever, bell-crank levers 46 and 47 may be connected to the system of rods 35 and 36. These bell-crank levers may be pivoted on a suitable support 48. The 115 downwardly extending ends of these levers may be connected to a block 49 on which may be arranged a shoe 50 shaped so that the inclined cam-way on the elevator car can easily engage the same. This arrangement of levers is used when it is desired to give 120 the shoes or rollers large bearing surfaces and give an easy acting device, as the two levers will give a parallel motion to the shoe. As many levers can be arranged at the top and bottom of the elevator well as desired 125 so that any desired motion can be given to the lever 32. Thus a very efficient mechanism is provided for operating the automatic shut-off valve.

This cam and lever mechanism is not 130

claimed in this application for patent owing to the classification adopted in the Patent Office, but the same is claimed in a companion application filed by me November 8, 1909, Serial No. 526,680.

The general design of the mechanism herein described has been to make all the parts simple, efficient, easy of repair and so that they can be manufactured in large lots and 10 used interchangeably in different relative positions to meet the different locations encountered in adapting the mechanism to different plants.

The details and arrangements herein 15 shown and described may be greatly varied by a skilled mechanic without departing from the scope of my invention as expressed in the claims.

Having thus fully described my invention 20 what I claim and desire to secure by Letters-Patent is:—

1. A main valve comprising a casing, a valve formed by a tube carrying two packings, a motor piston carrying a packing of 25 the same diameter as the valve packings, and a fixed piston fitted inside of the valve tube, the parts being arranged so that the valve casing can have the same diameter throughout.

2. A main valve comprising a casing, a valve tube, two packings fitted thereon and separated by a bushing, said packings con-

trolling a to-and-fro passage, a motor piston separated from the valve tube by a hollow reduced bushing, a fixed piston fitting inside 35 of the valve tube, and openings through the reduced bushing and valve tube to admit pressure between the valve tube and the fixed piston, the packings controlling the to-and-fro passage and the motor piston being of the same diameter whereby the valve casing can be bored one diameter.

3. An automatic stop valve comprising a valve casing, a to-and-fro passage and a to-and-fro pipe offset from each other connected therewith, a lining fitted in said casing and having ports opposite said passage and said pipe, a valve comprising two packings mounted on a hollow stem or tube having inlets at its ends, a check valve or valves 45 controlling ports or openings in said tube, valve stems connected to said tube and extending out through stuffing boxes on both ends of the valve casing to balance the valve hydraulically, and operating means connected to one of said valve stems.

In testimony whereof I have hereunto set my hand, in the presence of two subscribing witnesses.

THURE LARSSON.
